Specification for Design.

Patented Jan. 3, 1922.

Application filed March 21, 1921. Serial No. 454,306. Term of patent 14 years.

To all whom it may concern:

Be it known that I, FRANK W. DE LUCHI, a citizen of the United States, residing at Oakland, in the county of Alameda and State of California, have invented a new, original, and ornamental Design for Bake Ovens, of which the following is a specification.

The figure is a perspective view of a bake oven, showing my new design.

I claim:

The ornamental design for a bake oven, as shown.

In testimony whereof I affix my signature.

FRANK W. DE LUCHI.
